CLAIM

The ornamental design for a golf ball package, as shown and described.

DESCRIPTION

FIG. 1 is a top perspective view of a new design for a golf ball package;

FIG. 2 is a left side view of the golf ball package shown in FIG. 1;

FIG. 3 is a top view of the golf ball package shown in FIG. 1; and,

FIG. 4 is a front side view of the golf ball package shown in FIG. 1.

The broken lines are shown for the purpose of illustrating parts of the article that form no part of the claimed design. The right-side view of the golf ball package of FIG. 1 is depicted as shown in FIG. 2 and the back-side view of the golf ball package of FIG. 1 is depicted as shown in FIG. 4.

1 Claim, 2 Drawing Sheets
